UNITED STATES PATENT OFFICE.

THOMAS REUBEN ERNEST, OF CHICAGO, ILLINOIS, ASSIGNOR TO CHICAGO APPARATUS CO., OF CHICAGO, ILLINOIS, A CORPORATION.

GAS TESTER.

Application filed May 15, 1922. Serial No. 561,173.

To all whom it may concern:

Be it known that I, THOMAS R. ERNEST, a citizen of the United States, and a resident of the city of Chicago, county of Cook, and 5 State of Illinois, have invented certain new and useful Improvements in Gas Testers, of which the following is a specification.

My invention relates to new and useful 10 improvements in gas testers, and more particularly to the type of testers employed where the combustion method of testing is used.

With the devices heretofore employed for 15 testing gases by the use of the combustion method, explosions were frequently caused by the burning of impurities in such gases, and the expansive force of such explosion usually broke the test tubes employed, such tubes being generally made of thin glass.

20 It is my object to provide a gas tester which will not become broken by the explosion of such burning impurities, but in which the expansive force of such impurities will be taken up and gradually dissipated 25 through the use of interconnected chambers and a fluid medium freely movable therein.

Another object is to provide means for 30 cooling the combustion chamber, preferably by providing a water jacket around said chamber, in view of which a far greater temperature may be used in testing the gas.

Other objects will appear hereinafter.

The invention consists in the combinations and arrangements of parts hereinafter described and claimed.

The invention will be best understood by reference to the accompanying drawings forming a part of this specification, and in which,

40 Fig. 1, is an elevational view of the device showing the arrangement and condition of the members before the test gas is admitted, all air being excluded from the burette and pipette and the connecting conduits;

45 Fig. 2, is an elevational view of my device showing the arrangement of the members during the second step, with a definite quantity of test gas drawn into the burette or graduated container;

50 Fig. 3, is an elevational view showing the gas moved into the pipette or combustion chamber, by the fluid in the burette and con-

nected leveling bulb, which is the position for burning impurities from said gas with 55 the electric mechanism;

Fig. 4, is a partial view similar to Fig. 2 showing the treated gas returned into the burette or graduated container, minus the impurities removed therefrom during the 60 combustion process, and

Fig. 5, is a top view of the removable stopper or closing member on the pipette, showing the vent or discharge opening there- 65 in.

My invention illustrated comprises a gradu- 70 ated container or burette 10, formed of thick glass about one-eighth inch in cross section, and having a contracted lower portion 11 with the final numbers of the scale 75 thereon to provide a close graduation of the gas during the test. The upper end of said container is formed into a contracted neck 12 provided with a two-way valve 13, while an intake spout 14 and a connecting pipe 15 extend from said valve. A cylindrical tube or housing 16 encloses said burette or 80 container, and a stopper 17, of rubber or similar suitable material, is loosely mounted on neck 12 and closes the upper end of said tube, while a similar stopper 18 is firmly seated in the lower end of said tube and an extension 19 of the contracted portion 11 passes through said stopper 18. A support- 85 ing member 20 surrounds the extension 19 and bears beneath stopper 18 to support said tube and container, said member 20 being clamped to the vertical shaft 21 of a suitable supporting stand by means of a suit- 90 able thumb screw, or the like, and a suitable holding member 22 embraces the upper part of tube 16 and is fastened on said shaft 21 by a thumb screw or in any suitable manner. A flexible tube or hose 23 connects ex- 95 tension 19 with a leveling bulb 24 which may be supported in an upper bracket 25 or in a lower bracket 25', as the case may require, both brackets being adjustably fastened on shaft 21. The tube 16 will be filled with a cold fluid, as water, to provide cooling 100 means for the burette and for the gases re- turned therein from the pipette or combustion chamber after the combustion of said gases.

I further provide my container with a 105 water-jacketed combustion chamber which

comprises a pipette or inner combustion chamber 26 of thick glass having its lower end open and in constant communication with a cylindrical glass tube or housing 27, which surrounds the pipette, a stopper 28 being firmly mounted in the lower end of said tube and seated on a supporting member 29, which is adjustably fastened on shaft 21 by a suitable thumb screw, while a holding or retaining member 30 embraces the upper end of said tube and is adjustably fastened on shaft 21. A stopper 31 is loosely seated in the upper end of tube 27 and contains a vent or discharge opening 32 to permit the escape of expanded fluid, and a neck 33 is formed on the upper end of the pipette, which extends loosely through an opening in said stopper 31, permitting said stopper to move upwards from said tube when considerable expansive force is developed in the combustion chamber or pipette. A curved pipe 34 is connected to the neck 33 and to the pipe 15 by means of short pieces of flexible tubing 35 and 36.

25 The means for heating the gases in the combustion chamber comprises a large solid nickel electrode 38 firmly mounted in stopper 28, and a thin platinum wire 40 is attached to the curved upper end 39 of said 30 nickel electrode. A wire 41 is coiled around the electrode 38 and has a curved portion 42 for engaging the inner wall of the pipette to retain the electrodes in position therein. The lower end of the platinum electrode 40 is attached to a coiled wire 43 which retains proper tension in said electrode and is adjustably fastened to a large copper wire 44, with a set screw 45, said member 44 also passing through the stopper 28. Coupling members 46 and 47 are connected, respectively, to members 38 and 44 with suitable set screws, and carry set screws 48 and 49 for attaching said members to electric wires 50 and 51 connected with a suitable source 45 of electricity 52. Suitable covering tubes 53 and 54 are provided around the members 38 and 44, respectively.

In use the tester is mounted on a suitable stand, as indicated in the drawings, and the 50 water-jacket 16 is substantially filled with water or a similar cooling fluid, the water-jacket 27 being likewise substantially filled. All the air is then expelled from the burette or graduated container 10 and the pipette or combustion chamber 26 and the conduits connecting the same, by filling said burette, conduits, and pipette, and by partly filling the leveling bulb 24 connected to the burette by means of the hose 23, and proper 55 manipulation of the valve 13, the leveling bulb being then supported in its elevated position and the parts being arranged as shown in Fig. 1. The intake spout 14 is thereafter connected with the container of 60 the gas to be tested, and the valve turned to

position shown in Fig. 2, at the same time the leveling bulb is lowered, as shown in said figure, whereby the water descends in the container and a definite quantity of gas is drawn into said container, substantially as 70 indicated in Fig. 2 of the drawings. The valve is then turned into the position shown in Fig. 3, while the leveling bulb is again placed in its elevated position, as shown in 75 said Fig. 3, whereupon the water rises in the burette and forces the gas through the connecting conduit 34 into the pipette or combustion chamber, thereby forcing the water out of the open lower end of said chamber into the surrounding water-jacket elevating 80 the water therein substantially to the position shown in said Fig. 3. The valve is then turned to closed position and the electric current turned on for several minutes, heating the platinum electrode 40 and burning 85 out the impurities in said gas. If during this combustion test the burning of such impurities should cause an explosion, the expansive force of such explosion will force the water or fluid medium downward in the combustion chamber 26 and from it into the surrounding water-jacket 27, forcing the air above the water, and occasionally some of the water, out through the vent 32, and if the explosion is of a violent character then 90 the air and water rising suddenly in the water-jacket 27 will lift the stopper 31 upwards and escape freely, thereby preventing any breakage of the combustion chamber or any part of the gas tester. After this combustion test the gas, minus consumed impurities is returned into the burette by turning the valve, as indicated in Fig. 4, and lowering the leveling bulb until all the gas from the pipette and connecting conduit has 100 been forced back into the burette, the height of the water in the burette indicating the amount of tested gas remaining after removal of the impurities by said combustion 105 test, as indicated in Fig. 4, by the level of the water in the contracted portion 11 of the burette.

By providing a cooling medium or water-jacket for both the burette and pipette a greater temperature may be employed in the combustion test than with the former devices, since the water surrounding the pipette will constantly cool the same and will enable the gases to be returned therefrom to the burette at nearly the same temperature as when taken from the burette, thus enabling tests to be made in rapid succession without changing the water surrounding the burette, as was formerly required at frequent intervals.

While I have illustrated and described the preferred form of construction for carrying my invention into effect, this is capable of variation and modification without departing from the spirit of the invention, I,

therefore, do not wish to be limited to the precise details of construction set forth, but desire to avail myself of such variations and modifications as come within the scope of 5 the appended claims.

Having described my invention, what I claim as new and desire to secure by Letters Patent is:

1. A gas tester comprising means for 10 measuring gas; means for cooling said measuring means; a combustion chamber; connections between said chamber and measuring means; and means for cooling said chamber and for absorbing any explosive 15 force occurring during the test.

2. A gas tester comprising means for measuring gas; means for cooling said measuring means; a combustion chamber; connections between said chamber and measuring 20 means; means for cooling said chamber with a fluid and thereby absorbing explosive force produced by said test; and electric means for causing combustion in said chamber.

25 3. A gas tester comprising a graduated container; a water jacket surrounding said container; a combustion chamber; fluid connections between said container and chamber; and a water jacket surrounding said 30 chamber, said combustion chamber and its water jacket being arranged for gradually dissipating explosive force occurring in said chamber.

4. A gas tester comprising a graduated 35 container; cooling means therefor; a chamber for testing said gas; means connecting said chamber and container; electric means for causing combustion of the gas in said chamber; and a fluid container for cooling 40 said chamber, said container and chamber having communication for dissipating explosive force produced by said test.

5. A gas tester comprising a graduated container; means for cooling said container; 45 a combustion chamber having fluid connection with said container; and a tube surrounding said chamber and having open communication therewith.

6. A gas tester comprising means for 50 measuring gas; means operatively connected thereto for making a combustion test of said gas; and means connected with said test means for absorbing any explosive force occurring during said test.

55 7. A gas tester comprising means for measuring gas; a combustion chamber operatively connected thereto; and means connected with and surrounding said combustion chamber for dissipating the shock produced by explosion of impurities during the 60 test of said gas.

8. A gas tester comprising a combustion chamber; and a fluid chamber having open communication therewith for permitting explosives in said combustion chamber to ex-

pand by moving fluid therefrom to prevent breaking of said chamber.

9. A gas tester comprising a combustion chamber of thick glass and a fluid chamber surrounding the same, said chambers being 70 arranged to have fluid move freely from one to the other to prevent breaking of said chambers by the explosions during the test.

10. A gas tester comprising a combustion chamber; a fluid chamber surrounding the 75 same, said chambers being arranged to have fluid move freely from the combustion chamber to the fluid chamber; and a fluid escape or vent in the upper part of said fluid chamber.

80 11. A gas tester comprising means for making a combustion test of gas; means for cooling the said test means and the enclosed gas; and means for dissipating expansive force caused by explosions in said tester.

85 12. A gas tester comprising a combustion chamber; a water-jacket surrounding said combustion chamber; fluid communication between the lower part of said jacket and chamber; and a top on said jacket adapted 90 to be opened through the force of explosion in said combustion chamber.

95 13. A gas tester comprising a combustion chamber; a water-jacket surrounding said combustion chamber; fluid communication 95 between the combustion chamber and jacket; and a top on said jacket having a fluid vent and being adapted to be opened by the sudden explosion in the combustion chamber.

100 14. A gas tester comprising a combustion chamber; a water-jacket surrounding said combustion chamber; fluid communication between the combustion chamber and jacket; a top on said jacket having a fluid vent and being adapted to be opened by the sudden 105 explosion in the combustion chamber; and electric means for heating said combustion chamber.

110 15. A gas tester comprising a graduated container; means for cooling said container; a combustion chamber; a water-jacket therefor; fluid connections between said chamber and container; a valve therein; fluid connections between said chamber and its water-jacket; and a bulb and pliable tube for 115 causing fluids to move in said container and chamber.

16. A gas tester comprising a burette provided with an intake and a bulb and hose; a housing surrounding and supporting said burette and adapted to contain a cooling medium; a pipette and fluid conduit between said burette and said pipette; a water-jacket for said pipette; fluid connections between said pipette and its water-jacket; electric 120 heating means extending into said pipette; and means at the top of said jacket for releasing explosive pressure caused in the 125 pipette.

17. The method of testing gas, which 130

comprises expelling air from a measuring tube and a combustion chamber by means of a liquid; leading the test gas into said measuring tube; transferring said gas to said chamber by fluid containing means; consuming impurities in the gas by electric means in said chamber; absorbing shocks occurring in said chamber through explosion of impurities in said gas; and returning the 10 remaining gas to the measuring tube by said

fluid containing means to note the per cent of impurities consumed.

In testimony whereof I have signed my name to this specification in the presence of two subscribing witnesses.
